UNITED STATES PATENT OFFICE.

NEIL CROWTHER, OF NEW YORK, N. Y.

DESIGN FOR A FOUNTAIN PEN OR SIMILAR ARTICLE.

Application filed March 5, 1926. Serial No. 16,792. Term of patent 3½ years.

To all whom it may concern:

Be it known that I, NEIL CROWTHER, a citizen of the United States, residing at New York city, in the county and State of New York, have invented a new, original, and ornamental Design for a Fountain Pen or Similar Article, of which the following is a specification, reference being had to the accompanying drawing, forming part thereof.

The figure is a perspective view of a fountain pen or similar article, showing in dotted lines at the lower end, the use of the design for a pencil.

I claim:

The ornamental design for a fountain pen or similar article, as shown.

NEIL CROWTHER.
